CLAIM

The ornamental design for an angled liquid level, as shown and described.

DESCRIPTION

FIG. 1 is a top, front and left side perspective view of an angled liquid level showing my new design;

FIG. 2 is a front elevational view;

FIG. 3 is a left side elevational view, the right side elevational view being a mirror image;

FIG. 4 is a rear elevational view; and,

FIG. 5 is a bottom plan view thereof.

FIG. 1 has been drawn on an enlarged scale with respect to FIGS. 2-5.

FIG. 2.

FIG. 4.

FIG. 5.
